UNITED STATES PATENT OFFICE.

ISAAC TODD, OF BELFAST, IRELAND.

STEAM BOILER.

Application filed September 30, 1920. Serial No. 413,766.

To all whom it may concern:

Be it known that I, ISAAC TODD, of 22 Mountcollyer Avenue, Belfast, Ireland, a subject of the King of Great Britain and 5 Ireland, have invented certain new and useful Improvements in Steam Boilers, of which the following is a specification.

This invention relates to steam boilers and its object is to provide improvements 10 therein.

Under my invention I provide an improved device for circulating water in a steam boiler, said device comprising a pump casing, a tubular member attached to the 15 boiler and supporting said casing at the normal water level in the boiler, a pipe leading from the interior of said casing to the bottom of the water space, a pump in said casing, a spindle extending from the 20 pump through said tubular member and means for imparting motion thereto, whereby water is drawn through said pipe from the bottom of the water space and is discharged by said pump near the surfaces in 25 the boiler where the heat is greater.

The pump or water lifting device draws the water from one part of the water space at the coolest part of the boiler and discharges it at another part thereof, in proximity or on to a heating surface or surfaces.

The object of circulating the water as described is to pass as much of same as possible over the furnace plates and to keep 35 changing the water around the plates continuously so that more heat is taken up by the water than if the water were lying dead around the furnace plates. The continuous circulation of the water around the heating 40 surfaces causes the steam to be made more gently, and less water is liable to be carried over with the steam when the boiler is being forced for steam. Usually the steam is generated violently over the fire and furnace plates, and water is sometimes carried 45 over with the steam in large quantities and passed to the engine from which it returns to the boiler as cold feed.

The invention will now be described with 50 reference to the accompanying drawings, whereon:—

Fig. 1 is a cross sectional view of a horizontal steam boiler having two furnaces and showing the water circulating device there- 55 in.

Fig. 2 is a sectional plan view on the line $x-x$, Fig. 1, of a portion of the boiler and showing the water circulating device.

Fig. 3 is a cross sectional view of a horizontal marine steam boiler having three furnaces and showing the water circulating device in position in the boiler. 60

Fig. 4 is a sectional elevation of the boiler shown at Fig. 3.

In carrying out my invention as shown at Figs. 1 and 2, I employ a pump a in a casing a^1 , located near the crowns of the furnaces c^1 , and at, or about, the normal water level in the boiler. A pipe b puts the casing a^1 into communication with the dead water space at the bottom of the boiler d . Water is drawn through the pipe b into the casing by the action of the pump a and it is discharged therefrom through orifices in the casing, on to or near the crowns or in 70 the vicinity of the furnaces c^1 thereby brushing away the film of water which clings to the furnace plates and is one of the main losses of heat. One authority (Austin) gives this as .004 of one inch in thickness, hence the necessity for a pump to wash 75 away this layer. The resistance of the plate itself is insignificant in comparison with the resistance of this film of stagnant water. The screw of the pump a is shown secured 80 to a spindle a^2 which passes through a pipe a^3 and stuffing box e to the outside of the boiler. 85

The tube a^3 is screwed at one end to the stuffing box e and at its other end to the cover a^4 of the pump casing a^1 . A pulley f is secured on the spindle a^2 and may be driven by a belt or otherwise from any suitable source of power. 90

In the form of the invention illustrated in Figs. 3 and 4 the pump is shown near the tops of the combustion chambers. It communicates with the dead water space by a pipe b and is driven from the exterior of the boiler as described with reference to 100 Figs. 1 and 2. If desired, the pump may be located near the furnace crowns as in the previous arrangement. 105

Having now fully described my invention what I claim and desire to secure by Letters Patent is:—

In a steam boiler, a water circulating device comprising in combination, a pump casing, a cover for said casing, a tubular member attached, at one end, to the boiler 110

and, at the other end, to said cover, means securing said cover to said pump casing so as to leave discharge orifices therebetween, a pipe leading from the interior of said casing to the bottom of the water space of the boiler, a pump rotatably mounted in said casing, a spindle for said pump extending through said tubular member, a steam tight joint round said spindle, and a

pulley on said spindle outside the boiler, 10 all substantially as set forth.

In testimony whereof I affix my signature in presence of two witnesses.

ISAAC TODD.
